UNITED STATES PATENT OFFICE.

CORNELIUS BRAUN, OF LOUISVILLE, KENTUCKY.

DESIGN FOR A FIREPLACE-FRONT.

SPECIFICATION forming part of Design No. 25,360, dated April 7, 1896.

Application filed January 16, 1896. Serial No. 575,791. Term of patent 3½ years.

To all whom it may concern:

Be it known that I, CORNELIUS BRAUN, a citizen of the United States, residing at Louisville, in the county of Jefferson and State of Kentucky, have invented and produced a new and original Design for a Fireplace-Front; and I do declare the following to be a full, clear, and exact description of the same, reference being had to the accompanying drawings, forming a part thereof.

In the drawings, Figure 1 is a front view of my fireplace-front. Fig. 2 is a side edge view; Fig. 3, a top edge view, and Fig. 4 a vertical sectional view through the line *x-x*.

The leading feature of my design consists in the shape of the top piece of the grate-frame, which is flared in a curvilinear manner outward from its top toward the bottom, the outward flare beginning just below its top line, and also flared upward curvilinearly from its ends toward the middle, the flare beginning just outside the inner line of the side pieces and rising to meet the flare from the top, thus forming a hood, and the shape of the summer front, which is a plane surface rectilinear in outline flared outward near its top to conform to the contour of the lower edge of the hood-piece, having a flange on its upper edge. On each end of the side pieces is represented, in relief, a vase standing upright on a brick pedestal, and extending upward from the vase along the side piece a conventionalized cattail-flag plant. At each of the upper corners of the frame is represented a conventionalized lily with four leaves on its stalk,

as shown, and in the middle of the hood a flower-pot with a conventionalized narcissus in two branches bent down oppositely on each side of the pot and spread along horizontally toward the ends of the hood. In the center 40 of the smooth open field of the summer front is represented a raised oval medallion having embossed on it in profile the head and neck of a young woman with hair tied in a Grecian knot behind and frizzed in front. Above 45 the medallion is a conventionalized flowering vine and below a similar vine turned up at each end and running up in front and rear of the medallion, all forming a sort of frame for the medallion.

50 A are the side pieces of the frame; *a-a*, the vase and plants on same.

B is the top or hood piece of the frame; *b*, the hook on back of same adapted to hold the summer front in place; *b'-b'*, the corner flower 55 ornaments, and *b²* the central flower ornament; and C is the summer front; *c*, the flange on its top edge; *c'*, the outward flare at its top adapting it to the contour of the lower edge of the hood; *c'*, the center medallion, and *c²* 60 the conventionalized wreaths around same.

What I claim is—

The design for a fireplace - front herein shown and described.

In testimony whereof I affix my signature 65 in presence of two witnesses.

CORNELIUS BRAUN.
